UNITED STATES PATENT OFFICE.

ELIZA D. MURFEY, OF NEW YORK, N. Y.

IMPROVEMENT IN BEARINGS AND PACKINGS.

Specification forming part of Letters Patent No. 117,558, dated August 1, 1871; antedated July 21, 1871.

To all whom it may concern:

Be it known that I, ELIZA D. MURFEY, of New York, county of New York, State of New York, have invented an Improvement in Bearings and Packings, of which the following is a specification:

My invention relates to that class of bearing and packing materials employed as substitutes for the usual metallic bearings and packings; and my improvement consists of animal skins, retaining the hair or fleece, and impregnated with plumbago or its equivalent, as described hereafter.

In my patent of July 12, 1870, No. 105,361, is described a bearing and packing material, consisting of a sheet of leather, paper, or other material, to which, in some instances, a flocy surface is imparted by means of pickers, so that plumbago or other substance or composition applied to the said surface may penetrate into the latter and become inseparably a part of the same. This mode of imparting a flocy surface to skin or leather requires special mechanism, the employment of which it is the object of my present invention to avoid. I take an animal skin having the hair or fleece upon the same, and to the flocy side I apply powdered plumbago, or a mixture containing powdered plumbago or its equivalent, and, by any suitable mechanism, work the material among the mass of hair or wool, after which the whole is compressed to impart a uniform surface to the impregnated side of the skin, which may then be cut into strips or rings, to be employed in boxes for packings and bearings in the same manner as the materials heretofore patented by me for the same purpose.

Without limiting myself to any especial means of impregnating the skin, or to the use of any special impregnating material,

I claim—

A material for bearings and packings, consisting of animal skin, retaining the fleece or hair, and impregnated with plumbago or its equivalent.

In testimony whereof I have signed my name to this specification in the presence of two subscribing witnesses.

ELIZA D. MURFEY.
